UNITED STATES PATENT OFFICE.

GUIDO HORN, OF WEISSENSEE, NEAR BERLIN, GERMANY.

APPARATUS FOR HOLDING THE THREAD TENSE IN CIRCULAR-BRAIDING MACHINES.

1,343,452.

Specification of Letters Patent. Patented June 15, 1920.

Application filed December 29, 1916. Serial No. 139,669.

To all whom it may concern:

Be it known that I, GUIDO HORN, a citizen of the German Empire, residing at Weissensee, near Berlin, in the Kingdom of 5 Prussia, Germany, have invented certain new and useful Improvements in Apparatus for Holding the Thread Tense in Circular-Braiding Machines; and I do hereby declare the following to be a full, 10 clear, and exact description of the invention, such as will enable others skilled in the art to which it appertains to make and use the same.

In circular braiding machines in which 15 the spools are at an invariable distance from the points of braiding, the threads are, as a rule, held tense by direct braking of the spools. Such brakes are usually in the form of flaps which, under spring pressure, are forced against the body or runs of the spools. The pressure of such springs varies according to their tension and the diameter of the spools, and, consequently, the resistance to the taking off of the thread 20 varies also. If it becomes necessary to revolve backward braiding machines having such brakes, all the threads will become loose. The object of my invention is to provide an apparatus for use in circular 25 braiding machines of that class in which the bobbins or spools are suspended transversely so that the spindles of the bobbins are at right angles to the axis of the braided fabric, and which will effect a constant 30 braking action so as not only to make up for the variations in tension caused by variations in the diameter of the spools but also, on the machine being revolved backward, maintains the threads tense by taking them back for a sufficient distance. 35 Braiding machines of this character are shown and described in Letters Patent of the United States to Jones, 889,311, granted June 2, 1908, and Beauregard, No. 862,436, granted August 6, 1907. The object of my 40 invention necessitates a construction that requires little space. The thread braking levers known in thread spooling machines, the action of which is increased by guiding 45 the very rapidly moving thread over several guides between two fixed points situated at each end of the lever, cannot be used in the present instance. I provide short levers at an angle to each other which 50 are arranged to revolve together between two fixed points only, for receiving the

thread supply and regulating the thread tension. These levers, the revolution of which is limited to what is indispensable, are separated from the spools which are provided with separate brakes. The alternate action will only occur when the thread is being consumed and fresh thread has to be supplied from the spool. The temporary diameter of the spool is without influence 60 on the thread tension which only depends on the spring tension of the lever.

Reference is to be had to the accompanying drawings in which—

Figure 1 is a sectional elevation of the 70 preferred form of my thread tensioning device.

Fig. 2 is a plan view thereof, and

Fig. 3 illustrates the operation of the 75 auxiliary thread brake.

As illustrated, the spindle 14 of a spool 4 is held in the carrier 1^a.

Fixed on said spindle is a brake disk 15 the band of which is indicated at 16. One end of the band is secured to a pin 17^a, while 80 its other end is attached to a lever 27 which is pivoted at 28. An adjustable spring 29 holds the band 16 tense.

Parallel to the spindle 14 of spool 4 is a shaft 30 which carries a member 31. The 85 shaft is so held by means of an adjustable spring 33 that the member 31 has a tendency to move toward the spool 4. An eccentric groove 32 is formed in shaft 30 which is engaged by the free end of lever 27 when 90 member 31 moves nearer to the spool. The shaft 30 and its member 31 will in future be referred to as the thread spanner.

On the central portion of the spool carrier is fixed a thread guide 34 and a shaft 35. 95 This shaft is recessed as at 36 and rigidly connected to a lever 37 which, together with pin 38, acts as an automatic detector. A spring 39 presses on shaft 35 which spring may be adjusted by a screw 40.

The operation of the apparatus is as follows:

The thread passes from spool 4 below guide 34 and over the thread-spanner 30, 31. From here, it passes below pin 38 of the detector through recess 36 of shaft 35 and over spring 39 to the braiding point. When, 105 during the delivery of the thread to the braiding mechanism, the thread spanner is moved away from the spool beyond a predetermined degree, the eccentric groove 32 of shaft 30 exerts pressure on lever 27, re-

ducing the tension of band 16 until more thread is free to be delivered from the spool. This relieves the tension of the thread so that the thread-spanner is free to return to its initial position under the action of spring 33, while simultaneously lever 27 is released by the eccentric groove 32 so that the brake band 16 is again put under tension. The play of the thread-spanner is such that the length of thread which becomes released when the machine is revolved backward is held tense. Only when such revolving is continued for a certain length of time the spools must also be turned backward to wind up the surplus length of thread.

When the braiding machine is in operation, the heavier upwardly directed end of detector 37 has a tendency to swing to the outside owing to centrifugal action. This is prevented because the tense thread raises pin 38. When, however, the spool is finished or the thread breaks and its tension is thereby reduced, the weft fork swings to the outside and automatically stops the machine. As the detector 37 is rigidly connected to shaft 35, the shaft will revolve simultaneously, displacing groove 36 so that it no longer allows the thread to pass over spring 39. The thread is now clamped between shaft 35 and spring 39 which replaces the tension of the thread so that it cannot be drawn into the braid. This action of the auxiliary thread brake is clearly shown in Fig. 3.

35 I claim:

1. In a thread tensioning device of the character described, for braiding machines, in combination with the thread spool and its carrier, a thread spanner between said spool and carrier for braking said spool, and a detector over which the thread is guided, operated by the centrifugal power for automatically stopping the machine upon the

stoppage in the feed of the thread, and an auxiliary thread clamp for preventing the ends of the broken thread to be drawn into the braid.

2. In a thread tensioning device of the character described for braiding machines, in combination with the spool of the machine and its carrier, a shaft between spool and carrier having an eccentric groove, a hoop member on said shaft, a lever fulcrumed below said shaft and adapted to be engaged by said groove, a band guided over said spool and secured to said member, a detector operated by centrifugal action for automatically stopping the machine upon stoppage in the thread supply, and an auxiliary clamping device for clamping the loose thread ends and preventing them to be drawn into the braid.

3. In a thread tensioning device of the character described for braiding machines, in combination with the spool of the machine and its carrier, a spring controlled shaft between spool and carrier having an eccentric groove, a hoop member on said shaft, a lever fulcrumed below said shaft and adapted to be engaged by said groove, a band guided over said spool and secured to said member, a detector secured to the central portion of the carrier comprising a lever and pin, adapted to be operated by centrifugal action for automatically stopping the machine upon stoppage in the thread supply, a spring over which the thread is drawn, means to adjust said spring, and means for clamping the loose broken ends of the thread and preventing the same to be drawn into the braid.

In testimony whereof I hereunto affix my signature in the presence of two witnesses.

GUIDO HORN.

Witnesses:

HENRY HASPER,
ALLEN J. JUNGS.
